UNITED STATES PATENT OFFICE.

ELBERT H. CARROLL, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

WIRE-DRAWING MACHINE.

1,072,085

Specification of Letters Patent. Patented Sept. 2, 1913.

Application filed January 10, 1910. Serial No. 537,186.

To all whom it may concern:

Be it known that I, ELBERT H. CARROLL, a citizen of the United States, residing at Worcester, in the county of Worcester and 5 Commonwealth of Massachusetts, have invented a new and useful Improvement in Wire-Drawing Machines, of which the following is a specification, accompanied by drawings forming a part of the same, in 10 which—

Figure 1 represents a side view of a wire drawing block and die holder, with the latter in a raised position. Fig. 2 is a side view of a wire drawing block and die holder, 15 with the latter in its lowest position. Figs. 3 and 4 represent side views of the die holder showing the side opposite to that represented in Figs. 1 and 2, Fig. 3 showing the holder in a raised position and Fig. 4 20 in its lowest position.

Similar reference characters refer to similar parts in the different figures.

My present invention relates to means for supporting the die holder of a wire drawing 25 machine in different positions relatively to the rotating wire drawing block, and it consists in the construction and arrangement of parts as hereinafter described and pointed out in the annexed claims.

Referring to the accompanying drawings 30 1 denotes a wire drawing table or bench on which is mounted a rotatable wire drawing block 2, provided with a gripping mechanism 3, which may be of any suitable 35 and known form of construction for the purpose of seizing the end of the wire to be drawn. The gripping mechanism 3, as is usual in devices of this class, is attached to or carried by the upper portion of the 40 rotatable block. The lower portion of the rotatable block is provided with a beveled casting-off flange 4 as is common in machines of this class. Mounted upon the table 1 and in suitable relation to the rotatable wire drawing block is a die holder 5 45 in which the wire reducing dies are held and clamped in position by a clamping screw 6. The die holder 5 is pivotally connected by a horizontal pin 7 with the upper 50 end of a stud 8 rotatable in a vertical bearing 9 attached to the wire drawing table or bench by bolts 10, constituting a swiveled connection between the table and the die holder.

When the proper reducing die has been

placed in the die holder the free end of the wire which has previously been reduced for a certain distance is passed through the die and seized by the gripping mechanism 3. In order to bring the line of draft in alignment with the axis of the reducing die I raise the die holder, which is normally supported upon the table 1, into the position shown in Fig. 1 by means of a lifting lever 11, pivoted at 12, upon one side of the die 65 holder, and having a short supporting arm 13 which rests upon the top of the table 1. When the lifting lever 11 is rocked into the position shown in Figs. 1 and 3, the movement of the arm 13 over the surface of the 70 table 1 rocks the die holder on its pivotal pin 7, thereby raising the free end of the die holder, as shown in Figs. 1 and 3. In the operation of raising the die holder 5, the free end of the arm 13 is carried slightly 75 past a vertical plane passing through the center of the pivot 12, as indicated by the broken line 14, 14, and the lifting lever in that position is brought against a stop 15 which holds the lever from rotation against 80 the strain applied to the free end of the arm 13. In this position the opening in the die holder is pointed toward the gripping mechanism 3, but a sufficient distance below the 85 direct line of draft, as indicated by the broken line 16, Fig. 1, in order that when the slack between the gripping mechanism and the die holder is taken up by the rotation of the block 2, the die holder 5 will be 90 raised by the strain upon the wire sufficiently to allow the arm 13 to clear the table 1 and enable the lever 11, which stands at an inclination to a vertical plane, to fall by 95 gravity into the position shown in Figs. 2 and 4, its falling movement being checked by the contact of the arm 13 with the stop 17. The lifting lever 11 acts as a counterweight which is held from acting while the arm 13 is held in contact with the table 1, owing to the free end of the arm 13 passing 100 slightly past the vertical plane of the axis of the lever. As soon, however, as the arm 13 is relieved of the weight of the die holder, the lever 11 acts by gravity to rock the arm 13 and remove the support of the die holder 105 which then gradually descends, causing the wire to be wound in a spiral on the drawing block 2. The descent of the die holder then determines the character of the spiral coil 110 about the block 2. As the wire is wound

around the rotating block 2, each successive coil is wound nearer the casting-off flange, eventually bringing the line of draft into a horizontal plane corresponding with the 5 casting-off flange, against which each succeeding coil of wire is then wound, the winding of each coil pushing the preceding coils upward upon the conical surface of the drawing block 2.

10 I claim,

1. In a wire drawing machine, comprising a rotating block and a gripping mechanism, a supporting table, a die holder pivotally connected to said table, means for 15 supporting said die holder in a raised position slightly below the line of initial strain on the wire in the operation of wire drawing, said die-holder supporting means becoming automatically released when strain 20 is applied to the wire.

2. The combination with a supporting table, a wire drawing block and a gripping mechanism, of a die holder pivotally connected to said table, a swinging lever pivoted on said die holder having a supporting arm arranged to contact with said table and support said die holder in a raised position, said lever arranged to swing by gravity and move said arm out of contact with the table 25 when said arm is relieved of the weight of the die holder.

3. The combination with a supporting table, a wire drawing block and a gripping mechanism, of a die holder pivotally connected to said table, a lifting lever pivoted to said die holder and having one arm arranged to contact with the table and support said die holder in a raised position, with the weight of said lever applied to 35 swing said arm out of contact with said table when relieved of the weight of the die 40

holder, and a stop to limit the movement of said arm.

4. In a wire drawing machine, a table, a rotating block, a gripping mechanism, a die 45 holder, means pivoted to said die holder for supporting said holder in a raised position slightly below the line of initial strain upon the wire in the operation of wire drawing, said die-holder supporting means becoming 50 automatically released when strain is applied to the wire.

5. A wire drawing machine comprising a horizontal supporting table, a wire drawing block mounted on said table, a horizontal 55 die holder for a die through which the wire is drawn, said die holder pivotally mounted on said table, a lever pivotally attached to said die holder, said lever provided with a supporting arm arranged to contact with said table and raise said die holder into an inclined position as said lever is swung on its pivot, and means for limiting the swinging movement of said lever.

6. In a wire drawing machine, the combination of a table, a rotating wire drawing block, a wire gripping mechanism connected with said block, a die holder pivotally supported upon said table, means for supporting the die holder in a raised position 70 against its weight said die-holder supporting means becoming automatically released as soon as strain is applied to the wire, thereby allowing the die holder to descend by gravity and carry the wire down the 75 block.

Dated this fourth day of January 1910.

ELBERT H. CARROLL.
